VELOCIPED

Carl E. Cordrey, 4710 N. Libby, Oklahoma City, Okla.

Filed Oct. 20, 1965, Ser. No. 87,635

Term of patent 14 years

(Cl. D34—15)

FIGURE 1 is a perspective view of a velocipede, showing my new design as it appears when viewed from the right rear thereof.

FIGURE 2 is a perspective view of the velocipede showing my new design as it appears from the left rear thereof.

FIGURE 3 is a plan view of the velocipede as it appears when viewed from below or beneath the velocipede.

I claim:

The ornamental design for a velocipede, substantially as shown.
